UNITED STATES PATENT OFFICE.

AUGUST BELLINGRATH, OF EAST ORANGE, NEW JERSEY, ASSIGNOR TO AUGUST GOERTZ & CO., A CORPORATION OF NEW JERSEY.

BAG FRAME.

Application filed December 21, 1923. Serial No. 681,930.

This invention relates, generally, to improvements in bag frames; and, the present invention has reference, more particularly, to a novel and simply constructed bag frame 5 for use more particularly with ladies' hand bags, pocketbooks, and the like.

The present invention, therefore, has for its principal objects to provide a simply constructed bag-frame, comprising two sets 10 of bag-frames, the frame-sections of which are provided with a novel means of pivotal connection between them, whereby a strong and rigid pivotal connection of the two bag-frames and their respective frame-sections 15 is obtained.

Other objects of the present invention not at this time more particularly enumerated, will be fully evident from the following detailed description of the same.

With the several objects of the present invention in view, the said invention consists, primarily, in the novel bag frame hereinafter more fully set forth; and, the said invention consists, furthermore, in the 25 novel arrangements and combinations of the various devices and parts, as well as in the details of the construction of the said parts, all of which will be more fully described in the following specification, and then finally embodied in the clauses of the claims, which 30 are appended to and which form an essential part of the said specification.

The invention is clearly illustrated in the accompanying drawings, in which:—

Figure 1 is a front elevation of a bag-frame, showing one embodiment of the principles of the present invention; and Figure 2 is a top-edge view of the same, the frame-sections of the bag-frame being represented 40 in their closed relation.

Figure 3 is a side-edge view, showing on an enlarged scale, one of the hinged portions of the bag-frame, and Figure 4 is a vertical sectional representation of the same, 45 said section being represented as being taken on line 4—4 in said Figure 3, looking in the direction of the arrow in said figure.

Figure 5 is a collective perspective representation of the hinge-portions of the frame-sections, and the various parts employed in connection with the hinge-connections of the bag-frame.

Figure 6 is an inner face view of the hinge-portions of the inner frame of the bag-frame, the parts shown being represented in their relative positions when about to be secured in their assembled relations; and Figures 7 and 8 are similar views of said portions, the parts being shown in their detached relation.

Figure 9 is an inner face view of the hinge-portions of the outer frame of the bag-frame, the parts shown being represented in their relative positions when about to be secured in their assembled relations; and Figures 10 and 11 are similar views of said portions, the parts being shown in their detached relation.

Figure 12 is a front elevation of a slightly modified construction of bag-frame made according to and embodying the principles of the present invention; Figure 13 is a side edge view, showing one of the hinged portions of the said bag-frame; and Figure 14 is a transverse vertical sectional representation of the same, said section being taken on line 14—14 in said Figure 13.

Similar characters of reference are employed in all of the said above described views, to indicate corresponding parts.

Referring now to the several figures of the drawings, the reference-character 1 in Figures 1 and 2, indicates a complete bag-frame, made according to and embodying the principles of the present invention, comprising an outer bag-frame 2 and an inner bag-frame 3, pivotally connected at their respective end-portions by means of hinge-connections 4, 4, in the manner and for the purposes to be presently more fully described.

Referring now more particularly to Figures 3 to 11 inclusive, it will be seen, that the outer bag-frame 2 comprises a pair of frame-sections 5 and 6 of the usual U-shaped cross-section, the respective leg-members of which are provided at their free ends with slots, as 7 and 8, and with outwardly curled elements, as 9 and 10, arranged in pairs, as shown and extending in opposite directions, thus providing pintle-receiving eyes, for the reception therein of pintles 11 and 12, substantially as shown in Figures 1, 3 and 4 of the drawings. Disposed within the

slots 7 and 8 of the respective frame-members is a connecting plate 13, said plate provided with holes or perforations 14 and 15. These holes or perforations are adapted to 5 be arranged in alinement with the respective pintle-receiving eyes 9 and 10, for the reception therein of the pintles 11 and 12, and to thereby produce the connected maintenance of the assembled parts by means of 10 the heads 16 and the riveted-over ends 17 of said pintles. At their upper edge-portions, the said frame-sections 5 and 6 are provided with any suitably formed locking or retaining means, as 18, for maintaining the closed 15 relation of the said frame-sections, but of such construction so that the said frame-sections can be readily brought into their opened or separated relation.

The inner bag-frame 3 also comprises a 20 pair of frame-sections 19 and 20 of the usual U-shaped cross-section, the respective leg-members of which are provided with ears 21 and 22, respectively formed with perforations 23 and 24. In assembling these members, the ears 21 and 22 are placed upon each other, with the perforation 23 registering with the perforation 24, as indicated in Figure 6 of the drawings. The previously mentioned connecting plate 13 is also provided 25 with another hole or perforation 25 for the reception of a connector-stem or rod 26, the said stem or rod 26 having its end-portion 27 preferably rigidly secured in the perforation 25 against turning, by means of a rivet-head 28. Upon the other end-portion 29 of the said connector-stem or rod 26 are oscillatorily mounted the registering perforated ears 21 and 22 of the inner frame-sections 19 and 20. To prevent lateral movement 30 of the inner bag-frame thus oscillatorily mounted upon the connector stems or rods 26, and to maintain the proper relation of the inner bag-frame 3 with the outer bag-frame 2, spacing devices in the form of the tubes 30 are mounted upon the said stems or rods 26, as indicated in Figures 1 and 4 of the drawings, washers, as 31 and 32 being also mounted upon said stems or rods 26, upon opposite sides of the registering pivot-ears or lugs 21 and 22, and the end-portion of the rod or stem which extends beyond the washer 32 being riveted-over, so as to provide a retaining head 33.

At their upper edge-portions, the said frame-sections 19 and 20 are also provided with any suitably formed locking or retaining means, as 34, for maintaining the closed relation of the said frame-sections, but of such construction so that the said frame-sections can be readily brought into their opened or separated relation.

Referring now to Figures 12, 13 and 14 of the drawings, it will be seen, that the outer bag-frame comprises a pair of frame-sections 35 and 36 of the usual U-shaped cross-section,

the respective leg-members of which are provided with perforated ears or extensions 37 and 38.

The reference-character 39 indicates a connecting plate, similar in construction to the previously mentioned connecting plate 13, the said plate 39 being provided with a pair of perforations 40, one of which is shown in Figure 14 of the drawings, and which are adapted to be alined with the perforations of the ears or extensions 37 and 38, for the reception of suitable pivot-pins or eyelets 41, and whereby the said connecting plate 39 is pivotally or oscillatorily connected with the respective ears or perforations 37 and 38, and hence with the respective frame-sections 35 and 36. The said connecting plate 39 is also provided with another hole or perforation 42, see Figure 14, in which is arranged and secured by means 85 of a riveted-over portion or head 45 the reduced shank-portion 44 of a connector rod or stem 43 provided at its opposite end-portion with another reduced shank-portion 46 and a riveted-over portion or head 47. 90

The inner bag-frame in this construction also comprises a pair of frame-sections 48 and 49 of the usual U-shaped cross-section, the respective leg-members of which are provided with ears or lugs 50 and 51 respectively formed with perforations 52 and 53. As shown the herein-above mentioned reduced shank-portion 46 of the connector rod or stem 43 is arranged in the alined perforations 52 and 53 of the said ears or lugs 50 and 51, in a manner that the frame-sections 48 and 49 are capable of a pivotal or oscillatory motion upon said reduced shank-portion 46, the riveted-over portion or head 47 of course maintaining these parts in their 100 assembled and operative relation, as will be evident. 105

At their upper edge-portions the outer and inner bag-frames are respectively provided with suitable locking or retaining means, as 54 and 55, or the like. 110

Of course I am aware that some changes may be made in the general arrangements and combinations of the several devices and parts, as well as in the details of the construction of the said parts, without departing from the scope of the present invention as set forth in the foregoing specification, and as defined in the clauses of the claims, which are appended thereto. Hence, I do not limit my invention to the exact arrangements and combinations of the various devices and parts, as described in the foregoing specification, nor do I confine myself to the exact details of the construction of the said parts, as illustrated in the accompanying drawings. 115

I claim:

1. A two-part bag-frame comprising an outer and an inner frame, said outer frame 130

consisting of a pair of frame-sections, the ends of the leg-portions of said frame-sections being slotted, the adjacent end-portions of each leg-portion being provided with oppositely extending pintle-receiving eyes, connecting plates arranged in the slots of said leg-portions, each connecting plate being provided with perforations in alignment with the eyes of said leg-portions, pintles extending through said aligned eyes and perforations, a connector stem extending from each connecting plate, said inner frame consisting of a pair of frame-sections, and the ends of the leg-portions of the said last-mentioned frame-sections being provided with perforated ears oscillatorily mounted upon the said connector stems for oscillatorily disposing the inner bag-frame within the outer bag-frame.

20   2. A two-part bag-frame comprising an outer and an inner frame, said outer frame consisting of a pair of frame-sections, the ends of the leg-portions of said frame-sections being slotted, the adjacent end-portions
25   of each leg-portion being provided with oppositely extending pintle-receiving eyes, connecting plates arranged in the slots of said leg-portions, each connecting plate being provided with perforations in alignment
30   with the eyes of said leg-portions, pintles extending through said aligned eyes and perforations, a connector stem extending from each connecting plate, said inner frame consisting of a pair of frame-sections, and the
35   ends of the leg-portions of the said last-mentioned frame-sections being provided with perforated ears oscillatorily mounted upon the said connector stems for oscillatorily disposing the inner bag-frame within
40   the outer bag-frame, combined with a spacing tube mounted upon each stem between the connector plate and one of said perforated ears of the inner bag-frame.

3. A two-part bag-frame comprising an outer and an inner frame, said outer frame consisting of a pair of frame-sections, the ends of the leg-portions of said frame-sections being slotted, the adjacent end-portions of each leg-portion being provided with oppositely extending pintle-receiving eyes, connecting plates arranged in the slots of said leg-portions, each connecting plate being provided with perforations in alignment with the eyes of said leg-portions, pintles extending through said aligned eyes and perforations, a connector stem extending from each connecting plate, said inner frame consisting of a pair of frame-sections, and the ends of the leg-portions of the said last-mentioned frame-sections being provided with perforated ears oscillatorily mounted upon the said connector stems for oscillatorily disposing the inner bag-frame within the outer bag-frame, combined with a spacing tube mounted upon each stem, and washers upon

each stem, said washers being arranged upon opposite sides of the registering ears of the frame-sections of the inner bag-frame.

4. A two-part bag-frame comprising an outer and an inner frame, said outer frame consisting of a pair of frame-sections, the ends of the leg-portions of said frame-sections being slotted and provided with oppositely extending pintle-receiving eyes arranged in pairs adjacent to said slots, connecting plates arranged in the slots of said leg-portions, each connecting plate being provided with perforations, and each perforation being in alignment with a pair of eyes, a pintle extending through each pair of eyes and the perforation in alignment therewith, a connector stem extending from each connecting plate, said inner frame consisting of a pair of frame-sections, and the ends of the leg-portions of said last-mentioned frame-sections being provided with perforated ears oscillatorily mounted upon the said connector stems for oscillatorily disposing the inner bag-frame within the outer bag-frame.

5. A two-part bag-frame comprising an outer and an inner frame, said outer frame consisting of a pair of frame-sections, the ends of the leg-portions of said frame-sections being slotted and provided with oppositely extending pintle-receiving eyes arranged in pairs adjacent to said slots, connecting plates arranged in the slots of said leg-portions, each connecting plate being provided with perforations, and each perforation being in alignment with a pair of eyes, a pintle extending through each pair of eyes and the perforation in alignment therewith, a connector stem extending from each connecting plate, said inner frame consisting of a pair of frame-sections, and the ends of the leg-portions of said last-mentioned frame-sections being provided with perforated ears oscillatorily mounted upon the said connector stems for oscillatorily disposing the inner bag-frame within the outer bag-frame, combined with a spacing tube mounted upon each stem between the connector plate and one of said perforated ears of the inner bag-frame.

6. A two-part bag-frame comprising an outer and an inner frame, said outer frame consisting of a pair of frame-sections, the ends of the leg-portions of said frame-sections being slotted and provided with oppositely extending pintle-receiving eyes arranged in pairs adjacent to said slots, connecting plates arranged in the slots of said leg-portions, each connecting plate being provided with perforations, and each perforation being in alinement with a pair of eyes, a pintle extending through each pair of eyes and the perforation in alinement therewith, a connector stem extending from each connecting plate, said inner frame consisting of a pair of frame-sections, and the ends of

the leg-positions of said last-mentioned frame-sections being provided with perforated ears oscillatorily mounted upon the said connector stems for oscillatorily disposing the inner bag-frame within the outer bag-frame, combined with a spacing tube mounted upon each stem, and washers upon

each stem, said washers being arranged upon opposite sides of the registering ears of the frame-sections of the inner bag-frame. 10

In testimony that I claim the invention set forth above I have hereunto set my hand this 20th day of December, 1923.

AUGUST BELLINGRATH.
